BRACKET FOR TRAILER SWAY CONTROL
DEVICEWilliam L. Rendessy, 8028 N. 14th Place,
Phoenix, Ariz. 85020

Filed June 12, 1973, Ser. No. 369,262

Term of patent 14 years

Int. Cl. D8—08

U.S. Cl. D8—236

FIG. 1 is a perspective view of top, one side and one end of the bracket for trailer sway control device with clamp plate, bolts and a part of the tongue of the trailer shown in dash lines for illustrative purposes only;

FIG. 2 is a perspective view of the other side, bottom and other end of the bracket shown in FIG. 1;

FIG. 3 is a cross-sectional view of FIG. 2 taken along the line 3—3 in the direction of the arrows;

FIG. 4 is an enlarged front view of the bracket shown in FIG. 1; and

FIG. 5 is a top view of FIG. 4.

I claim:

The ornamental design for the bracket for trailer sway control device, as shown and described.
